AUTOMATIC TELEPHONE SWITCH

Filed July 5, 1922

Inventor:
Victor F. Miller

by W. C. Beatty AMY.

Patented June 9, 1925.

UNITED STATES PATENT OFFICE.

VICTOR F. MILLER, OF NEW YORK, N. Y., ASSIGNOR TO WESTERN ELECTRIC COMPANY,
INCORPORATED, OF NEW YORK, N. Y., A CORPORATION OF NEW YORK.

AUTOMATIC TELEPHONE SWITCH.

Application filed July 5, 1922. Serial No. 572,909.

To all whom it may concern:

Be it known that I, VICTOR FRED MILLER, a citizen of the United States of America, residing at New York in the county of New York and State of New York, have invented 5 certain new and useful Improvements in Automatic Telephone Switches, of which the following is a full, clear, concise, and exact description.

10 This invention relates to automatic switching apparatus and more particularly to coordinate switches of the type adapted for establishing connections in an automatic telephone exchange system.

15 The invention is particularly adapted to a switching system of the type disclosed in Patent No. 1,515,735 issued to Charles L. Goodrum et al, on November 18, 1924, but it will be apparent to those skilled in the 20 art that this invention may be applied equally well to perform other switching functions with few changes in the operating circuit.

The object of this invention is to provide 25 an economical and improved form of coordinate switch which will be simple, durable and reliable in operation.

In accordance with the foregoing object, the principal feature of this invention resides in the provision of a novel mechanism for selectively operating the active contacts in a coordinate switch structure comprising in general, normally disengaged active and 35 passive contacts, a lifting arm provided with a notched insulating card which is adapted to operatively engage the active contacts, and conjointly operating coordinate bars for operating said arms. Other features of invention and advantages will 40 appear from the following detailed description and by the claims appended hereto, reference being had to the accompanying drawing in which Fig. 1 is a partial front assembly view of said switch. Fig. 2 is a 45 sectional view of Fig. 1 showing a set of active contacts in an operated position. Fig. 3 is a perspective detail view of a lifting arm together with its operating card. Fig. 4 is a fragmentary plan view of the relative 50 positions of the vertical operating bar and a lifting arm on one of the horizontal operating bars in their normal and off-normal positions.

The sets of grid conductors comprising

the wires 1, 2, 3, 4 and 5, 6, 7, 8, etc. are 55 securely fastened at their ends to fixed members not shown.

Supports 9 and 10 are of insulating material and are disposed at right angles to the direction of the lengths of the grid conductors and on them are mounted the flexible wire contact springs 12, 13, 14, 15 and 16; 17 60 18, 19, etc. The supports 9 and 10 may be of considerable length and may carry any desired number of sets of contact springs 12, 13, 14, 15, depending upon the switch capacity desired. For simplicity of illustration, however, only two such sets are shown on support 10 in the sectional view of Fig. 2.

70 The free ends of each set of contact springs 12, 13, 14, 15, etc., are adjusted normally to rest on the laterally extending arms 20, 21, 22, 23, etc., of the insulating strips of the grid conductors.

75 With each vertical row of active contact sets there is associated a vertical rotatable bar 24 which is provided at one end with an arm 25 in operable engagement with the arm 26 of an armature 27 arranged to be attracted by an electromagnet 28 whereby the bar 24 is rotated out of its normal position against the resistance of spring 41 in response to each energization of said electromagnet. On each vertical bar 24 there is 80 provided a number of cams 29, each individual to a set of contact springs.

85 With each set of grid conductors 1, 2, 3, 4, etc., there is associated a horizontal rotatable bar 30, each of which is provided at 90 one end with an armature 31 and an electromagnet 32 whereby the bar is rotated from normal to off-normal position. Each horizontal bar 30 is provided with a number of pivotally arranged arms 33 which are movable in the horizontal plane and held in non-operated position by means of springs 40. Each of these arms 33 carries an operating card 34 having a number of obliquely disposed notches 35, 36, 37, 38 and each is 95 adapted to be moved into operative relation with the active contacts, but it will be noted that normally arms 33 and card 34 thereon are free to move in a vertical path to one side of their respectively associated active contact wires.

100 This is true, however, only while the cam 29 associated with any arm 33 is in its nor-

mal position as shown at 39, Fig. 1, wherein the arm 33 is shown in its off normal ineffective position.

When the vertical bar 24 is rotated out of its normal position by electromagnet 28 the cams 29 are moved into operable engagement with associated arms 33.

Movement of bar 30 results in lifting the active contact wires through the engagement of said wires into the notches of the operating card so as to permit the active contact wires 12, 13, 14 and 15, to engage the grid conductors 5, 6, 7 and 8, respectively. The obliquely disposed notches in the operating card 34 when in operative relation with the flexible wire contact springs, causes lifting arm 33 in its operated position attained through the actuation of cam 39, to deviate in its upward movement still further from its normal path, so that when the lifting arm has completed its movement the contact springs are in engagement with its associated group conductors, and the arm 33 is therefore clear of its associated cam 29 as shown in Fig. 4 thereby permitting subsequent operations of the bar 24 without disturbing any co-existing connections. The operated grid bar together with arm 33 thereon remains in their off normal position throughout the duration of the connection but the vertical bar 24 may be immediately restored to normal. The cam 29 in its operated position is entirely clear of its associated arm 33 so that any subsequent movement of said cam for the establishment of coexisting connections, is ineffective to disturb the connection already established.

What is claimed is:—

1. In a switching mechanism, sets of active conductors, sets of passive conductors, an arm having rotary and pivotal movements simultaneously for operating said active conductors, the resulting movement of said arm being in a diagonal direction, an operating card mounted on said arm, rotary bars and means including said rotary bars for moving said arm to effect interengagement of said sets of active and passive conductors.

2. In a switching mechanism, sets of passive contacts, sets of active contacts, an arm having rotary and pivotal movements simultaneously thereby causing said arm to move in a diagonal direction, a card carried by said arm for operatively engaging said active contacts, said arm being normally movable in a path wherein it is ineffective to operate said active contacts, and means effective when operated, to cause said arm to deviate from its normal path to operate said active contacts.

3. In a switching mechanism, sets of normally disengaged passive and active contacts, an arm having rotary and pivotal movements simultaneously thereby causing said arm to move in a diagonal direction for

operating said active contacts, a card carried by said arm, said arm being movable in a path wherein it is ineffective to operate said active contacts, and a cam which when operated is effective to cause said arm to deviate from its normal path to operate said active contacts.

4. In a switching mechanism, sets of normally disengaged active and passive contacts, an arm having rotary and pivotal movements for operating said active contacts, the resulting movement of said arm being in a diagonal direction, a card carried by said arm, said card being movable in a path wherein it is ineffective to engage said active contacts, means for operating said arm, a cam, and means for moving said cam into the path of said arm whereby said arm is caused to deviate from its normal path into operative relation with said active contacts.

5. In a switching mechanism, sets of normally disengaged passive and active contacts, a diagonally movable arm for operating said active contacts, a card carried by said arm, a cam, and means for moving said cam whereby said cam is operable to cause a subsequent operation of said arm to effect connection between said contacts, said connection being unaffected during its continuation by subsequent operation of said cam.

6. In a coordinate switch structure, sets of passive contacts arranged in rows, sets of active contacts arranged in rows coordinate to the first mentioned rows, a rotatable bar associated with a row of active contacts, a cam fixedly attached to said bar, another rotatable bar associated with a row of passive contacts, an arm carried by second mentioned bar, a card carried by said arm for operatively engaging said active contacts in notches which correspond in number to the active contacts, means for operating the first mentioned bar to move said cam, and means for operating the second mentioned bar to move said arm, a movement of said cam followed by a movement of said arm being effective to move said card into operable engagement with said active contacts.

7. In a coordinate switch structure, sets of normally disengaged passive and active contacts arranged in coordinate rows, a pair of coordinately disposed bars for selectively operating said active contacts, a cam carried by one of said bars, a movable member carried by the other of said bars, a notched operating card carried by said member for operatively engaging said active contacts, and means for rotating said bars, said cam in its off-normal position being disposed in the normal path of said member whereby said member in its movement from normal is caused to deviate from its normal path and by means of the notches in said card to

deviate further from its normal path beyond contact with the said cam to a point where a connection between the passive and active contacts is established.

5 8. In a switching mechanism, sets of passive contacts, sets of active contacts, a selective mechanism for operating said active contacts, including a rotatable bar, a rigid arm pivotally arranged on said bar, a 70
10 notched operating card on said arm, another rotatable bar, and a cam carried by the second rotatable bar, a movement of said cam in its off-normal position followed by a movement of said arm being effective to 75
15 interengage said contacts through the engagement of said card with said active contacts.

9. In a switching mechanism, a plurality of sets of normally disengaged passive and 20 active contacts, a selective mechanism for said contacts, including a rotatable bar, a pivotally arranged arm on said bar, a notched operating card carried by said arm, said card being adapted to be moved into 25 engageable relation with said active contacts, another rotatable bar, and a cam arranged on the second rotatable bar, said cam when operated being effective to cause said arm to deviate from its normal path to engage and move said active contacts into engagement with said passive contacts.

30 10. In a switching mechanism, a plurality of coordinate rows of sets of passive and active contacts, a rotatable bar for each row 35 of active contacts, and a rotatable bar for each row of passive contacts, each of said first-mentioned bars being provided with a plurality of cams, one for each set of passive contacts associated therewith, each of 40 said second mentioned bars being provided with a plurality of operating arms, one for each set of active contacts associated therewith, an operating card comprising obliquely 45 parallel slots, fixedly attached to each of said operating arms, the conjoint rotation of one of each of said bars being effective to move said card in a diagonal direction into operative engagement with a set of active contacts, and the continued rotation 50 of the said second-mentioned bar being also effective to move said card in a vertical direction to establish a connection between associated sets of active and passive contacts.

55 11. In a switching mechanism, normally disengaged passive and active contacts, a selective mechanism for said contacts including a rotatable bar, an arm, a card on said arm for operatively engaging said active contacts, said arm being normally movable by the rotation of said bar in a path wherein the card does not engage the active contacts, and means selectively operable to cause said arm to deviate from its path during its 60 movement from normal wherein the card

engages the active contacts and effects interengagement between said active and passive contacts.

12. In a switching mechanism, sets of normally disengaged passive and active contacts, a selective mechanism therefor including a bar, a pivotally arranged arm on said bar, an insulating notched card on said arm for operatively engaging said active contacts, means for operating said arm in a path effective relative to said active contacts, and means for restoring said arm in non-operated position.

13. A coordinate switch comprising a set of passive contact members, a set of active contact members, a pivoted arm for operating said active members, a spring for returning said arm to normal, said arm having a cam surface and being normally operable ineffectively with respect to said active contact members, a cam, and means for moving said cam to cause a subsequent operation of said arm to be effective with respect to said active contacts.

14. In a coordinate switch structure, a set of grid conductors, a set of wire spring contacts tensioned downwardly and coordinately disposed to said conductors, a warp in said grid arranged to support said contacts, a pivoted arm for operating said contacts and a flexible member for returning said arm to normal.

15. In a coordinate switch structure, a grid comprising a set of bare wire conductors, a set of wire spring contacts coordinately disposed to and arranged to project through said grid, an insulative warp in said grid arranged to support said contacts, a pivoted arm for operating said contacts, and a plurality of camming surfaces on said 105 arm for effecting a rubbing connection between said conductors and contacts.

16. In a coordinate switch structure, a grid comprising a set of conductors, a set of wire spring contacts tensioned downwardly, a pivoted arm for operating said contacts, a warp in said grid for supporting said contacts in non-operated position arranged to position said contacts when said arm is released, an insulative member provided with a plurality of camming surfaces fixedly attached to said arm and arranged to be normally operable ineffectively with respect to said contacts, a cam, means for moving said cam to cause a subsequent operation of said arm to be effective with respect to said contacts, and a resilient member for restoring said arm to normal.

17. A coordinate switch comprising sets of contacts, a selective mechanism comprising a pair of cooperating bars, a pivoted member on one of said bars, normally rotatable in a path ineffective to establish a connection between said contacts, means on the other of said bars for causing said pivoted

member to deviate from its normal path to effect a connection between said contacts, and flexible means for restoring said pivoted member to normal when the bars are released.

18. A coordinate switch comprising a set of passive contacts, a set of active contacts, a selective mechanism comprising coordinately disposed operating bars, a cam on one of said bars, a pivoted member on the other of said bars, said member being nor-

mally rotatable in a path ineffective to establish a connection between said contacts, means selectively operable to cause said cam to position itself in the path of said pivoted member to effect a connection, and a resilient member attached to said bars for returning said pivoted member to normal when the bars are released. 15

In witness whereof, I hereunto subscribe 20
my name this 1st day of July A. D., 1922.

VICTOR F. MILLER.
